INVENTOR

BY Victor J. Evans

ATTORNEY

UNITED STATES PATENT OFFICE

OSCAR S. GAGE, OF TULSA, OKLAHOMA

RAILROAD TIE AND RAIL CLAMP

Application filed December 27, 1929. Serial No. 416,916.

My present invention has reference to a metal tie for railway rails, and means for fastening the rails thereon and the primary object of the invention is the provision of a simple but strong and sturdy tie which will support the rails in a manner that will prevent the tilting or canting thereof, and which likewise will afford the rails the same resiliency or yieldability as that afforded by a wooden tie.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

25 In the drawings:

Figure 1 is a side elevation of my improvement with the rails in applied position and the rails in section.

Figure 2 is a top plan view thereof.

30 Figure 3 is a section on the line 3-3 of Figure 2.

Figure 4 is a sectional view on the line 4-4 of Figure 1.

35 Figure 5 is a sectional view on the line 5-5 of Figure 2.

Figure 6 is a side elevation to illustrate a slight modification.

Figure 7 is a top plan view thereof.

40 Figure 8 is a fragmentary side elevation to illustrate a still further modified form of rail engaging clip or clamp.

Figure 9 is a perspective view of the said clip or clamp.

45 Figure 10 is a perspective view of a bail which may be employed.

As disclosed by the drawings the body 1 of my improved tie is in the nature of a metal channelled member. The tie 1, at the ends thereof preferably has its upper corners reduced and the upper edges of the reduced por-

tions are connected by transverse plates 2. The end walls of the tie, above the notched reduced corners thereof are disposed at an angle as indicated by the numerals 3, and the sides of the tie, adjacent to and at a suitable distance from the ends thereof are notched, as at 4, to provide seats for the rails 5. Inward of the notches the bottom of the tie is bent upwardly to form the same with lugs 6 and the outwardly extending and straight ends of these lugs are adapted to contact with the inner ends of rail blocks 7 which are disposed below the notches 4 and project into the notches. The rail blocks may be of hollow metal that afford a desired resiliency, but preferably the said blocks are short pieces of wood.

The sides of the tie 1, in a line with the inner edges of the base flanges of the rails 5 are either formed with or have fixed thereon centrally grooved plates 8 and overlying these plates there are the body portions 9 of rail engaging clips 10. The plates, at the upper portions thereof are formed with outwardly extending lugs 11, and passing through the body portions 9 of the clips 10 in the showing of Figures 2 and 4 of the drawings there are bolts 12 which are engaged by nuts 13 that contact with the under faces of the lugs 11.

Each of the rail supporting blocks 7 has one or both of its sides, from one of its ends formed with a depression 13', whose lower wall is arranged at a downward inclination, as indicated by the numeral 14. One or both of the inclined walls 3 of the tie have on the inner face thereof an inwardly extending flange 15 that merges into an inwardly directed horizontal flange or extension 16, and designed to be received between the walls 15 and 16 and likewise adapted to be received in the depressions 13' there are plates that afford rail clamps 17. The inner edges of these clamps are notched, as at 18, to receive the outer base flanges of the rails therein. The inner corners of the walls 16 are rounded and the ends of the rail clamps are preferably also rounded. The rounded corner of the wall 16 is designed to be contacted by the upper face of the clamp 17 and the rounded outer end of

each of the clamps 17 is designed to ride against and frictionally contact with the inclined walls 15. The walls 16 are preferably provided with upwardly extending bosses whose outer faces are inclined, the said bosses surrounding openings through which pass the shanks of bolts 19, the heads 20 of the said bolts being received in cages 21 formed on the under faces of the clamps 17 and the shanks 10 of the bolts have screwed thereon nuts 22 which rest on the bosses 23 of the walls 16.

As far as the description has progressed it will be noted that the hollow or channeled tie may be filled with the roadbed or have the 15 roadbed packed in the ends thereof against the blocks 7. Because of the contacting engagement of the clamps 17 with the walls 15 and 16 and because the said clamp forces the rail and consequently the block into tight engagement with the clip and with the stop lug 6 an outward movement of the block is prevented. To remove the rails it is merely necessary to unscrew the nuts 22 which permit the clamping blocks or plates 17 dropping 25 into the tie and into the depressions 13' in the sides of the rail block 7. The grooved plates 8 and the lugs thereon are contacted by the roadbed so that the liability of the longitudinal and tilting movement of the tie and 30 the rails thereon is effectively prevented. The rails themselves being engaged by the clips and clamps are effectively held from vertical or canting movement, while the frictional engagement between the clips and clamps is 35 binding but sufficient to permit of the necessary expansion and contraction of the rails.

A slightly different form of plate such as is illustrated in Figures 6 and 7 of the drawings may be employed. In this instance there 40 is arranged over the tie a slightly different form of clip, indicated by the numeral 24 and the body plate thereof is indicated by the numeral 25. The ends of the body plate 25 overlie the lugs 11. There is arranged beneath and along the sides of the tie a substantially U-shaped bolt 28 which is received in the grooves 8 and passes through the lugs 11 and through the ends of the body plate of the clip. The threaded ends of these substantially U-shaped bails or bolts are engaged 50 by nuts, as disclosed by the drawings.

When the rails are arranged at a curvature a clip 29 such as illustrated in Figures 8 and 9 is employed. This clip is in the nature of a block and is of a size to be received in the inner fishing spaces of the rails. The body portion 20 of the block or clip 29 is engaged by a bail or U-shaped bolt similar to that above described. The employment of the 60 U-shaped bolts provides both the sides and the bottom of the tie with enlargements in the nature of ribs against which the road bed contacts and which further hold the tie from movement in the roadbed.

65 It is believed the simplicity of my construc-

tion and the advantages thereof will be apparent to those skilled in the art to which such invention relates so that further description will not be required.

Having described the invention, I claim:

1. A channeled tie having grooved plates terminating in upper lugs on the sides thereof, blocks affording rail seats in the tie, stop elements in the tie for engaging in the blocks, rail clips for engaging with the inner base flanges of rails having lateral body portions fixed on the lugs, notched rail clamps for engaging the outer base flanges of the rails, said tie having angle walls on the inner ends thereof, one providing a fulcrum and the other an abutment for the clamps and removable and adjustable securing means between, the clamps and the fulcrum wall.

2. A channeled metal tie having its sides adjacent to its ends notched, rail blocks received in the tie adjacent to the notches thereof, stop elements in the tie for engaging the rail blocks, clips fixed to the tie for engaging with the inner base flanges of rails, notched bails providing rail clamps for engaging with the outer base flanges of the rails, said rail blocks having their sides notched to receive the clamps therein, said tie adjacent to the ends thereof having upstanding angle walls and horizontal walls, the latter providing fulcrums for the rail clamps and the former providing abutment walls for the ends of the said clamps and removable and adjustable means securing the clamps to the upper walls.

3. A channeled metal tie having its sides, adjacent to its ends, notched, rail blocks received in the tie adjacent to the notches thereof, stop elements in the tie for engaging the rail blocks, clips fixed to the tie for engaging with the inner base flanges of rails, notched bails providing rail clamps for engaging with the outer base flanges of the rails, said rail blocks having their sides notched to receive the clamps therein, said tie, adjacent to the ends thereof having upstanding angle walls and horizontal walls, the latter providing fulcrums for the rail clamps and the former providing abutment walls for the ends of the said clamps and removable and adjustable means securing the clamps to the upper walls, said means comprising bolts which are engaged by nuts and said clamps having cages to receive therein the heads of the bolts.

4. A channeled metal tie having grooved plates terminating in lugs on the sides thereof and having their said sides notched in a line with such lugs, rail blocks in the tie opposite the notches thereof, integrally formed stop lugs in the bottom of the tie to engage with the rail blocks, said rail blocks designed to have resting thereon rails, clips having laterally extending body portions which are arranged over the lugs, U-shaped bolts ar-

ranged beneath and along the sides of the tie to be received through the grooved plates passing through the lugs and the body portions of the clamps and said bolts being engaged by nuts, elongated plates having their inner edges notched to receive the outer base flanges of rails therein and providing rail clamps, said tie, adjacent to the ends thereof having upwardly extending 10 angular and horizontal walls, the former affording an abutment for the rail clamps and the latter a fulcrum element for the rail clamps, said blocks having their sides notched to receive the clamps therein and removable and adjustable securing elements 15 between the fulcrum walls and the clamps.

In testimony whereof I affix my signature.
OSCAR S. GAGE.
